CLAIM

The ornamental design for an aircraft seat, as shown and described.

DESCRIPTION

FIG. 1 is a right perspective view showing our new design of an aircraft seat;

FIG. 2 is a left perspective view of the aircraft seat of FIG. 1;

FIG. 3 is a front view of the aircraft seat of FIG. 1;

FIG. 4 is a back view of the aircraft seat of FIG. 1;

FIG. 5 is a left side view of the aircraft seat of FIG. 1;

FIG. 6 is a right side view of the aircraft seat of FIG. 1; and,

FIG. 7 is a top view of the aircraft seat of FIG. 1.

The dashed lines in FIGS. 1-7 depict a base beneath the aircraft seat which is environmental structure that forms no part of the claimed design.

The pattern of dotted lines shown on the front of the seat back and on the top of the seat bottom depict stitching in the seat cover and are part of the claimed design.
